UNITED STATES PATENT OFFICE.

GEORGE M. KLUG, OF IONIA, MICHIGAN.

FOUNDRY-CUPOLA.

1,135,025.

Specification of Letters Patent. Patented Apr. 13, 1915.

Application filed May 18, 1914. Serial No. 839,837.

To all whom it may concern:

Be it known that I, GEORGE M. KLUG, a citizen of the United States of America, residing at Ionia, in the county of Ionia and 5 State of Michigan, have invented certain new and useful Improvements in Foundry-Cupolas; and I do hereby declare the following to be a full, clear, and exact description of the invention, such as will enable others 10 skilled in the art to which it appertains to make and use the same.

This invention relates to foundry cupolas and has for its principal object the provision of means for removing the residue of molten 15 metal and slag from the cupola before dropping the bottom of the cupola and after the major portion of the metal has been withdrawn through the regular outlet. To this end I have embodied my invention 20 in the construction shown in the drawings and in which,

Figure 1 is a vertical section through the lower portion of a cupola equipped with my invention, said section being on the line 25 1—1, Fig. 2. Fig. 2 is a fragmentary view of the cupola from beneath. Fig. 3 is a view similar to Fig. 1 but with the auxiliary opening open for the discharge of the residue of material from the cupola, and Fig. 30 4 a detail showing a modification of my device.

Like reference characters refer to like parts throughout the several views of the drawing.

35 The vertical wall 1 of the cupola is lined with fire clay or similar heat resistant material and at the front thereof near the bottom of the cupola, said wall and lining are pierced to form the usual outlet opening 2 through 40 which the molten metal may be discharged to the spout 3 being carried thereby to any convenient receptacle. The bottom of the cupola is formed of two plates 4 of semicircular outline which are hingedly attached 45 to the wall 1 at diametrically opposed points, said plates being adapted to swing toward each other and be secured to form the bottom of the cupola as shown. Above the bottom thus formed a mixture of heat resist- 50 ant material 5 is placed forming a protective wall between the plates 4 and the molten metal and such material is of a thickness that its upper surface is below or in sub- 55 substantially the same plane horizontally as the outlet opening 2, and normally, the up-

per surface of the material 5 is formed concaved or dished with the lowest point of the surface at substantially the center of the cupola.

This construction described is the ordinary cupola structure when in running order and after as much of the molten metal has been removed as is possible through the outlet opening 2, there will always remain a residue of metal and slag. It is the practice 60 to drop the bottom plates 4 with this residue remaining in the cupola upon completion of a run of the cupola, and many times, the molten metal thus dropped will splash upon employees causing serious injury. I have 70 provided means to avoid this undesirable happening as follows. One of the bottom plates 4 is provided with an opening therein near the straight side thereof and in preparing the cupola for a run, a funnel 6 75 formed of fire clay or similar material is located with its smaller end in said opening, the funnel extending upwardly nearly to the upper surface of the material 5 when it is placed in the cupola as shown in Figs. 1 80 and 3. A circular plate 7, having in the edges thereof diametrically opposed notches 8 covers the said opening being retained in position against the lower side of the bottom plate 4 by retaining members 9 formed 85 from strips of metal and secured to the plate 4, each member 9 having an offset portion between which and the plate 4, the circular plate 7 is held. A handle 10 is fixed to the plate 7 and is of use in turning it back and 90 forth to position it for removal or to turn it so that the notches 8 will be away from the members 9 and the plate held in position.

With this construction, after the molten metal has been drawn off as much as possible 95 through the outlet opening 2, the plate 7 is removed by turning it so that its notches 8 are brought opposite the ends of the members 9 and a receptacle is located below the opening in the bottom plate, after which the material in the funnel 6 may be removed by use of a rod making an opening for the passage of the residue of molten metal and slag to the receptacle. In many cases the material 5 will readily drop through the opening 100 on removal of the plate 7 so that no removal of the material in the funnel is necessary. When the residue has been drawn off, the receptacle may be removed and the bottom 105 dropped in the usual manner, there being 110

- no danger of splashing molten metal as heretofore. It is of course understood that the upper surface of the material 5 may not always be concaved with the lowest portion 5 at the center of the cupola but that the lowest portion of the upper surface of said material may be variously located. In such case, the funnel 6 should be located adjacent said lowest point, and it is contemplated that the auxiliary outlet construction may be placed at any desired position with reference to the base or walls of the cupola such that it will best fulfil its desired functions.
- 15 The disclosure made is of a complete and operative embodiment of my invention, but such disclosures is to be taken as diagrammatic and illustrative of the invention and not as limiting it to any precise specific structure, other than made necessary by the terms of the appended claims.

I have shown in Fig. 4 a modification, for instance, in which a tube 6^a is used in place of a funnel shaped member, and the same supported by the margin of the plate 4, and the supports for the circular plate 7 are formed integral with the plate 4, as at 9^a. Various other modifications obviously may be used if preferred, without departing from the spirit of my invention.

Having fully described my invention, what I claim as new and desire to secure by Letters Patent is:—

1. A foundry cupola having a bottom and a vertical wall with an opening in the vertical wall providing an outlet for the removal of molten metal from the cupola, and means provided in the cupola for removal of the residue of molten material in the cupola below the level of said outlet opening.
2. A foundry cupola having a bottom and a vertical wall with an opening in the vertical wall providing an outlet for the removal of molten metal from the cupola, and means provided in the bottom of the cupola for removal of the residue of molten

material in the cupola below the level of said outlet opening.

3. A foundry cupola having a bottom provided with an opening therein, a funnel positioned in said opening, a plate covering the opening and against which the funnel rests, and means for detachably securing said plate over the opening.

4. A foundry cupola having a bottom provided with an opening therein, a funnel positioned in said opening and extending above the bottom, a closure for the opening comprising a plate and against which the funnel rests, and retaining members attached to the bottom and engaging said plate to retain it in position to close the said opening.

5. A foundry cupola having a bottom, a funnel extending through said bottom, a plate covering the lower end of the funnel, and retaining members attached to the bottom for retaining the plate in position to close the lower end of the funnel.

6. A foundry cupola having a bottom, a funnel extending through said bottom, a plate for closing the lower end of the funnel, notches in the plate and retaining members for holding said plate in position, said notches permitting the engagement of the plate and retaining members.

7. A foundry cupola having a bottom, a funnel extending through said bottom, a plate for closing the lower end of the funnel, spaced apart retaining members adapted to engage and hold the plate in position, said retaining members connected to the bottom, notches in the plate for permitting the engagement and disengagement of the plate and retaining members, and a handle connected to the plate for manual operation thereof.

In testimony whereof I have affixed my signature in presence of two witnesses.

GEORGE M. KLUG.
